(57) **CLAIM**

The ornamental design for a 90 degree female electrical connector with locking arm, as shown and described.

DESCRIPTION

FIG. 1 is a top, front, left side perspective view of my new design of a 90 degree female electrical connector with locking arm.

FIG. 2 is a top, rear, left side perspective view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front side elevational view thereof; and,

FIG. 8 is a rear side elevational view thereof.

The broken lines in FIGS. 1, 6 and 7 represent environment only, and form no part of the claimed design.

1 Claim, 3 Drawing Sheets
